ANTIFILTERING CLOSURE FOR PAPER BAGS

James S. Simpson, Auburn, N. Y., assignor to
Columbian Rope Company, Auburn, N. Y., a
corporation of New York

Application August 16, 1937, Serial No. 159,393

4 Claims. (Cl. 229—62)

This invention relates to improvements in closures for bags formed of paper or similar material and, particularly, for bags of that construction used as containers for granulated or pulverulent materials.

In the use of paper bags for materials such as cement, sugar, plaster of Paris, and the like, one or both ends of the bag have generally been closed by a seam of stitches transversely of the bag adjacent the end or ends of the paper walls, thus securing the walls together. The perforations formed in the paper walls by the needle piercing the same in stitching the seam are not fully closed by the stitches and, as a result, the 5 contents of the bag may sift or filter through these rather minute openings. For this reason, it has generally been the practice to provide auxiliary means for closing these perforations or openings, such means also, in some instances, serving to reinforce the seam. In each such prior instance, however, one or more difficulties or disadvantages have been encountered. For instance, where a member or cord made of cotton is used on bags containing sugar particles of cotton often detach 10 themselves, particularly while the bag is being emptied and fall into the mixture in which the sugar is being used, thus necessitating additional straining operations to remove such particles. On the other hand, if the bags are used for cement, capillary action often causes the contents of the bag to be damaged by moisture gaining access thereto. Paper members have been used in lieu of cotton but in every known instance of this nature, the construction or formation of said 15 member has been such as to rather seriously interfere with the bag closing operation, as by the paper deflecting the sewing needle or causing the needle to heat up and break or otherwise lowering the efficiency in sewing.

The primary object of the present invention, therefore, is to provide a bag closure and an anti-filtering member for the closure which will prevent loss of the bag contents by filtering through the openings made by the needle and which will 20 eliminate the difficulties previously set forth.

More specifically, the invention contemplates an anti-filtering member preferably in the form of a cord made of paper, the paper being crushed to form the cord with the creases extending parallel to the longitudinal axis of the cord. In other words, the paper is substantially free of 25 twist in the finished cord.

With these and other objects in view, the invention consists in certain details of construction and combinations and arrangements of parts, all

as will hereinafter be more fully described, and the novel features thereof particularly pointed out in the appended claims.

In the accompanying drawing—

Figure 1 is a face view of one end of a bag embodying the preferred form of the invention;

Fig. 2 is a sectional view on the line 2—2 of Fig. 1; and

Fig. 3 is a detail view of a short length of the present anti-filter cord, one end thereof being shown as having been opened out to more clearly illustrate the parallel disposition of the creases formed by crushing the paper in producing the cord.

As illustrated in Fig. 1, the end of the bag is closed by securing the walls of the bag together by stitching a seam across the same, the individual stitches of this seam being indicated at 10. The thread constituting the stitches does not completely fill the openings made by the needle piercing the bag wall, as previously mentioned and, hence, the use of the antifilter cord strip 11. The cord is shown in Fig. 3 and for reasons set forth above, it is made of paper crushed along lines parallel to each other and to the longitudinal axis of the cord. It will be noted that the stitches extend through the cord, but the cord being free of twist, there are no curving folds and, consequently, no tendency to deflect the needle during the sewing operation. Also, the crushed paper cord is easily penetrated by the needle, thus avoiding heating of the needle. Likelihood of damaging or breaking the needle, or reducing the efficiency of the sewing operation is, therefore, eliminated or reduced to a minimum.

Compared with the cotton filter cord, the present cord possesses greater strength. It is less expensive (foot for foot) than any of the previously used filter cords and, having no twist, it has an inherent tendency to lie flat on the surface of the bag and also tends to flow into or enter, and thus more efficiently close, the needle holes.

It will be understood that either or both ends of the bag may be closed by sewing and, if desired, a small sheet of paper 12 can be folded over the bag end, although this is not at all necessary. It has just been pointed out that the present cord possesses considerable strength so that it effectively reinforces the bag at the seam.

What I claim is:

1. A closure for paper bags which comprises a stitched seam for securing together the walls of the bag adjacent their ends, and a reinforcing antifiltering cord formed of crushed paper extending longitudinally of the seam with the

stitches passing through said cord, the creases in the paper formed by the crushing thereof extending substantially longitudinally of the cord and seam.

5 2. A closure for paper bags which comprises a stitched seam for securing together the walls of the bag adjacent their ends, and an antifiltering element formed of a crushed paper overlying the apertures in the bag walls formed by the stitches 10 passing therethrough, the stitches of the seam also extending through said element.

3. A closure for paper bags which comprises a stitched seam for securing together the walls of the bag adjacent their ends, and an antifiltering 15 means at each side of the bag overlying the apertures formed by the stitches extending through the bag walls, said means being formed of un-

twisted, crushed paper cord with the stitches extending therethrough, the creases in the crushed paper extending longitudinally of the seam.

4. An antifiltering element for preventing filtering of the contents of a paper bag through openings formed in the bag walls by the stitches forming the seam by which the walls are secured together for closing the bag, said element being formed of a crushed paper cord having creases therein, said creases being disposed substantially 10 parallel to the longitudinal axis of the cord and said cord being easily penetrated by a sewing needle in stitching the bag walls together whereby deflection and heating of said needle is minimized. 15
